UNITED STATES PATENT OFFICE.

EDWIN F. GALLOWAY, OF NEWARK, NEW JERSEY.

BANDAGE-WINDING DEVICE.

1,261,225.

Specification of Letters Patent.

Patented Apr. 2, 1918.

Application filed June 18, 1917. Serial No. 175,278.

To all whom it may concern:

Be it known that I, EDWIN FRANCIS GALLOWAY, a citizen of the United States, and a resident of Newark, in the county of 5 Essex and State of New Jersey, have invented certain new and useful Improvements in Bandage-Winding Devices, of which the following is a specification.

This invention relates generally to apparatus for winding sheet material and particularly relates to manually operable bandage winding devices.

In the art of winding and reeling sheet material, power-driven machines, of massive 10 and complicated structure, designed to be operated by trained and skilled workmen are in common use. Machines of this type fill, in a satisfactory manner, a distinct field in the art but are obviously not adapted for use 15 by individuals, or small groups of individuals, whose work is generally of a charitable nature and on a comparatively small scale and who, therefore, require simple, inexpensive and manually operable devices 20 that will, nevertheless, rapidly produce bandage rolls that are uniformly and compactly wound. The main object of the present invention is to provide a manually-operable bandage winding device that will satisfactorily fulfil these requirements.

Another object of the invention is to provide a device in which the necessary tension in the web for insuring the compact winding of the roll is automatically produced by the 35 action of the web itself in passing through the device.

With these and other objects in view, one feature of the invention consists in the provision of a winding device having web 40 smoothing means through which the web is threaded in such manner as to automatically produce sufficient tension therein to obtain a compact and uniformly wound bandage roll.

Another feature of the invention consists 45 in providing a winding device which can be clamped to the edge of a table or the like and through which the web is threaded across the edge of the table, through guiding and 50 turning means, into an accessible path parallel and adjacent the table edge. Other features of the invention will be referred to as the specification proceeds.

In the accompanying drawing there is 55 illustrated a preferred embodiment of the invention but it is to be understood that the

invention may be carried out by other embodiments different from that specifically selected for illustration.

Figure 1 is a side elevation of a device 60 embodying the invention and showing in dotted lines a web threading position of the web smoothing means.

Fig. 2 is a plan view of the device shown in Fig. 1.

Fig. 3 is a vertical longitudinal section of the device taken along the line 3—3 of Fig. 2.

Fig. 4 is a vertical sectional view on the line 4—4 of Fig. 3, of the reeling device showing a roll of wound web in position.

Fig. 5 is a vertical section of the device taken along the line 5—5 of Fig. 3.

Fig. 6 is a detail view of a modified form of means for holding the movable reel flange member in place.

In Figs. 1 and 2 of the drawing there is shown a complete embodiment of the invention in which a reeling device shown at 1 is arranged to draw a web of material 2 through a smoothing device 3 and a turning 80 means 4 supplied with a fixed gage member 5 and a movable gage member 6.

The device, as a whole, is supplied with a supporting base 7 adapted to be clamped to any suitable support, such as a table top 8, by 85 means of a clamping device 9. The reeling device 1 is made up of a core member 10 having a hexagonal or other formation suitable for gripping and turning the web.

The core member 10 is adapted to be withdrawn from its position when the bandage roll carried thereby has reached the desired 90 size. A suitable hand crank 11, attached to one end of the core member 10, provides for the manual operation of the device to effect 95

winding of the web. A fixed flange member 12, mounted in the frame member 7 at one side of the device, serves to guide one end of a roll of rewound material. During 100 the winding operation, the other end of the roll is preferably guided by a movable flange member 13 carried by a hollow supporting member 14 slidably mounted in the frame piece 7.

A spring 15 is arranged to continually press the movable flange member 13 into engagement with the other end of the corresponding roll.

In order to properly smooth the web as it is drawn into position on the reeling device, a smoothing device 3 is provided. This 110 device consists of a set of fixed rods 16 mounted in the frame so as to lie trans-

versely to the path of the web engaged thereby. The rods 16 are so spaced as to provide room therebetween for a plurality of similar rods 17 carried by a hinged frame 5 member 18 in such manner that the rods 17 are interposed in alternate arrangement when the frame 18 is moved to its closed position. By reference to Fig. 3 of the drawing, it will be seen that the relative 10 arrangement of the two sets of rods 16 and 17 causes the interposed web to pass through the series of rods in convoluted or waved formation so that a considerable part of the surface of each rod is brought to bear 15 against the face of some one of the other rods to exert a smoothing action on the web that will remove folds and wrinkles therefrom.

In order to exert a sufficient degree of 20 pressure on the web as it passes through these series of rods 16 and 17, the web is deflected from its natural path between the last rod of the series and the reeling device and is caused to pass over and bear against 25 a transversely mounted tensicing member 19 on the end of the swinging frame piece 18. It will be seen that by this arrangement the web operates to hold the swinging member in its closed position and in this 30 way causes pressure to be exerted on the web by the smoothing rods which not only enhances the smoothing action produced by the rods, but also brings about a compact and uniform winding of the web as it is 35 drawn to its place in the reeling device 1.

In order to thread the web through the smoothing device 3, it is necessary merely to raise the swinging member 18 from its closed 40 to an open position, as shown in dotted lines in Fig. 1, and to draw the web underneath the hinged end of the swinging member 18, thence underneath the complete series of 45 smoothing rods 17 carried by the swinging member, and thence over the transverse tensioning member 19 to the reeling device 1. It will be seen that when the end of 50 the web has been attached to the core member 10 by the simple expedient of wrapping the end of the web around the core member, a bandage roll can be formed by merely turning the hand crank 11, since any regulation that is required of the tension exerted on the web roll is automatically provided by the web itself as it 55 passes through the smoothing device and over the tension member 19.

Another important feature of the device resides in its adaptability for mounting along the edge of a table, such as is indicated at 8, and for drawing the supply of material over the edge of the table from any suitable receptacle mounted therebeneath. In order to effect this arrangement, a turning device 4 is provided which is set at such

an angle to the direction of the web path 65 through the machine as to produce a right angle turn in the web as is indicated at 20 in Fig. 2 of the drawing. The fixed gage member 5 is mounted on the upper side of the support 7 in alinement with the flange 70 member 12 of the reeling device so as to guide the corresponding edge of the web through the smoothing device into proper position on the web roll. The gage member 6 is provided for coöperation with the 75 web and, in order to provide for webs of different widths, the gage member 6 is preferably mounted on the supporting rod 21 slidably mounted in a channel 22 in the frame member and adapted to be fixed in 80 any desired position by means of the locking device 23. The gage member 6, as will be seen, engages the web 2 before the right-angle turn over the edge of the turning device 4 has been made. Preferably, the 85 slidable rod 21 is provided at its outer extremity with a transversely turned end 24 that serves to prevent displacement of the entering web from its path. It will be seen that by this arrangement, material can be 90 fed into the device across the edge of the table, whereupon it is diverted to a path parallel to, and closely adjacent, the table edge where it can be closely observed by the operator as it is wound into place on 95 the reeling device 1 through the accessibly located hand crank 11. It will be obvious that the web can be fed directly into the smoothing device 3 along the fixed gage member 5 without passing over the turning 100 device 4, if found desirable.

When the roll in the reeling device has reached the required size, it is a simple matter to remove it from its place by rotating the core shaft 10 in a reverse direction for 105 a few turns and withdrawing the core 10 bodily from its place. As will be seen, this frees the roll and it then can be readily slipped from its position between the flanges 12 and 13. 110

Instead of employing the spring 15 for holding the flange 13 in place, the hollow flange supporting member 14 may be clamped in any desired position in the corresponding divided end of the frame member 7 by means of the clamping screw 25 as shown in Fig. 6 of the drawing. 115

I claim:

1. A bandage winding device comprising: a reel shaft on which the material is wound, 120 a web tensioning device through which the web passes in a substantially horizontal path to the reel shaft, web turning means for directing the web from a substantially horizontal path at an angle to said first-named path into said tensioning device, web guiding means engaging one edge of the web along said first-named path, and web 125

guiding means engaging the other edge of the web along said second-named path.

2. A bandage winding device comprising: a reel shaft on which the material is wound, 5 a web smoothing device through which the web passes to the reel shaft, said smoothing device including a fixed member and a movable member, said members being adapted to engage the opposite sides of the interposed web, and means whereby the web holds the movable member in a position to engage and press the web into engagement with the fixed member.

3. A bandage winding device comprising: 15 a reel shaft on which the material is wound, a web smoothing device through which the web passes to the reel shaft, said smoothing device including a series of web engaging members mounted in fixed positions across 20 the path of the web and a hinged frame carrying a series of web engaging members adapted to be moved into positions between the fixed members to cause the interposed web to take a convoluted path, and a member 25 carried by said hinged frame over which

the web is passed to hold said frame in operative position.

4. A bandage winding device comprising: web reeling means, actuating means, for rotating said reeling means, located at one 30 side of the device, and web turning means, admitting infeeding of the web from the side on which the actuating means is located, for turning and leading said web to the reeling means. 35

5. A bandage winding device comprising: web reeling means, actuating means, for rotating said reeling means, located at one side of the device, and web turning means, admitting infeeding of the web from the 40 side on which the actuating means is located, for turning and leading said web to the reeling means, and a web smoothing means between the turning and reeling means. 45

Signed at New York, in the county of New York and State of New York, this 16th day of June 1917.

EDWIN F. GALLOWAY.
